UNITED STATES PATENT OFFICE

PAUL DIXON, OF ATLANTA, GEORGIA, ASSIGNOR TO J. P. STEVENS ENGRAVING CO.,
OF ATLANTA, GEORGIA, A CORPORATION OF GEORGIA

DESIGN FOR A SHEET OF WRITING PAPER

Application filed July 15, 1930. Serial No. 36,356. Term of patent 7 years.

To all whom it may concern:

Be it known, that I, PAUL DIXON, a citizen of the United States, and a resident of Atlanta, county of Fulton, and State of Georgia, have invented a new, original, and ornamental Design for a Sheet of Writing Paper, of which the following is a specification, reference being had to the accompanying drawings, forming a part thereof:

I claim:

The ornamental design for a sheet of writing paper as shown.

In testimony whereof I affix my signature.

PAUL DIXON.
